US00D692066S

(12) **United States Design Patent**
Miller et al.

(10) **Patent No.:** US D692,066 S
(45) **Date of Patent:** ** Oct. 22, 2013

(54) **CHIP RACK WITH INTEGRATED HOLE
CARD READER**

(75) Inventors: **Arthur C. Miller**, Las Vegas, NV (US);
Dean A. Isaacs, Las Vegas, NV (US)

(73) Assignee: **Tech Art, Inc.**, Las Vegas, NV (US)

(**) Term: **14 Years**

(21) Appl. No.: **29/399,000**

(22) Filed: **Aug. 8, 2011**

(51) **LOC (9) Cl.** 21-01

(52) **U.S. Cl.**

USPC **D21/392**

(58) **Field of Classification Search**

USPC D21/392; D99/34; 206/0.8, 315.1;
211/49.1; 53/254

See application file for complete search history.

GrayRobinson, P.A.

(57) **CLAIM**

The ornamental design for chip rack with integrated hole card reader, as shown and described.

DESCRIPTION

FIG. 1. is a left front perspective view of the design.

FIG. 2. is a top plan view thereof.

FIG. 3. is a right side elevational view thereof.

FIG. 4. is a front elevational view thereof.

FIG. 5. is a bottom plan view thereof.

FIG. 6. is a rear elevational view thereof.

FIG. 7. is a left side elevational view thereof.

FIG. 8. is a right front elevational view thereof.

FIG. 9. is a left rear perspective view thereof.

FIG. 10. is a right rear perspective view thereof.

FIG. 11. is a left front perspective view of a modified version of the design.

FIG. 12. is a top plan view thereof.

FIG. 13. is a right side elevational view thereof.

FIG. 14. is a front elevational view thereof.

FIG. 15. is a bottom plan view thereof.

FIG. 16. is a rear elevational view thereof.

FIG. 17. is a left side elevational view thereof.

FIG. 18. is a right front elevational view thereof.

FIG. 19. is a left rear perspective view thereof; and,

FIG. 20. is a right rear perspective view thereof.

The broken lines depict unclaimed environmental subject matter.

1 Claim, 20 Drawing Sheets
